(57) **CLAIM**

The ornamental design for a display screen with icon, as shown and described.

DESCRIPTION

FIG. 1 is a front view of a first embodiment of a display screen with a icon showing our new design;

FIG. 2 is a front view of a second embodiment of a display screen with a icon showing our new design;

FIG. 3 is a front view of a third embodiment of a display screen with a icon showing our new design;

FIG. 4 is a front view of a fourth embodiment of a display screen with a icon showing our new design;

FIG. 5 is a front view of a fifth embodiment of a display screen with a icon showing our new design;

FIG. 6 is a front view of a sixth embodiment of a display screen with a icon showing our new design; and,

FIG. 7 is a front view of a seventh embodiment of a portion of a display screen with a icon showing our new design. The broken lines illustrate the display screen and form no part of the claimed design.

1 Claim, 7 Drawing Sheets
